ADJUSTABLE VENT FOR DRIERS OR
SIMILAR ARTICLEBen R. Blumer, 201 S. Fillmore,
Kennewick, Wash. 99336

Filed July 10, 1969, Ser. No. 18,171

Term of patent 14 years

Int. Cl. D23—01

U.S. Cl. D23—40

FIG. 1

FIG. 2

FIG. 3

FIG. 4

FIG. 1 is a left front perspective view of the adjustable vent for driers or similar article embodying my new design;

FIG. 2 is a front elevational view of the within invention drawn to a smaller scale;

FIG. 3 is a rear elevational view thereof; and

FIG. 4 is a side elevational view of the within invention.

I claim:

The ornamental design for an adjustable vent for driers or similar article, as shown and described.
